United States Patent Office

Des. 178,707
Patented Sept. 4, 1956

178,707

RELIGIOUS CANDLE HOLDER

Wilbur J. Turcotte, Cohoes, N. Y.

Application May 17, 1956, Serial No. 41,528

Term of patent 14 years

(Cl. D48—2)

Fig. 1

Fig. 3

Fig. 1 is a side elevational view of a religious candle holder showing my new design;
Fig. 2 is an end elevational view; and
Fig. 3 is a plan view.

I claim:
The ornamental design for a religious candle holder,
as shown.
